TAPER

John C. Urbank, St. Paul, Minn.

Application July 26, 1943, Serial No. 496,148

6 Claims. (Cl. 67—22)

1

My invention relates to an improvement in tapers, and more particularly in that type of taper used in the lighting of candle wicks and the like.

Tapers are often used in church services for lighting candle wicks. A holder is usually provided comprising two tubular elements projecting from a handle and arranged in side by side relation. The ends of these tubular elements opposite the handle are usually bent in opposite directions, one to support a candle snuffer, and the other to contain the taper for lighting the candle. One end of this taper is preferably supported in a slideable clamp in the tube accessible through a slot in the side of the tube. The other end of the taper projects from the end of the tube and is lighted for the purpose of lighting one, or a series of candle wicks.

The candle carrying the wick is often supported in a cup arranged to catch candle drippings. Accordingly to bring the lighted taper into contact with the wick, it is sometimes essential that the projecting end of the taper be bent downwardly from the position in which it would normally leave the end of the tube. It has been attempted to bend the wick downwardly by grasping the projecting end of the wick and bending it in the desired direction. When this is done, however, the point of bend is directly adjacent the end of the tube. Accordingly, when the bent end of the taper is ignited and burns toward the tube end the end of the tube itself is heated so that the wax of the taper adheres thereto. As a result the taper freezes in the tube and can not be ejected by subsequent operation of the supporting clamp or slide.

It is an object of the present invention to provide a taper with a series of longitudinally spaced bending points therein located a predetermined distance apart. As a result the taper may be ejected from the tube end until one of the bending points of the taper is spaced outwardly from the end of the tube. Accordingly the free end of the taper may be bent at the bending point in any desired direction without affecting the portion of the taper close to the tube. As a result the burning portion of the taper is spaced somewhat above the end of the tube and the material forming the tube is not heated by the flame. As a result the tendency is not created for the taper to stick to the tube, and continued operation of the taper is simplified.

A feature of the present invention lies in the fact that the taper may be readily bent at a point spaced outwardly from the end of the tube,

2

rather than at the mouth of the tube. This feature is of importance, as heating of the tube will result when the taper is bent at a point adjacent the mouth of the tube.

5 A further feature of the present invention lies in the formation of points of bend in spaced intervals along the taper. In preferred form, circumferential grooves are provided in the taper at equal intervals. With such a construction the 10 taper may be bent with equal ease in any desired direction. If desired, however, the fold lines may be arranged along a transverse line of fold, in which case the bending of the taper in but one direction is facilitated. In such an instance 15 the taper should be mounted in a predetermined relationship to the tube. Points of bend could likewise be formed by transverse or circumferential grooves formed in the taper and later filled with softer wax. Similarly short links of soft 20 wax could be provided in the taper at intervals so as to simplify bending at these points.

A feature of the present invention lies in the fact that the heat created by the lighted end of the taper melts the wax of the taper adjacent 25 the flame and causes this wax to fill in the transverse or circumferential grooves about the taper before the flame reaches these grooves. As a result the taper burns as well at one point as at another and there is no danger of the taper going 30 out when the flame reaches one of the bending points previously described.

These and other objects and novel features of my invention will be more clearly and fully set forth in the following specification and claims.

35 In the drawing forming a part of my specification:

Figure 1 is an elevational view of a candle snuffer and candle lighter, showing the taper projecting therefrom.

40 Figure 2 is an enlarged sectional view through a portion of the candle snuffer and lighter.

Figure 3 is a view similar to Figure 2 showing the taper supporting device in taper receiving position.

45 Figure 4 is a plan view of a taper embodying the features of my invention.

Figure 5 is a modified form of taper, from that illustrated in Figure 4.

50 Figure 6 is a modified form of taper construction, differing from the forms illustrated in Figures 4 and 5.

The candle igniting and snuffing instrument is indicated in general by the numeral A, and is commonly used in church services. The instrument A embodies a handle 10 supporting a pair

3

of tubular elements 11 and 12, which are held in substantially parallel relationship by any suitable means, such as by the bands 13. The tubular member 11 is provided with a curved upper end 14 to which is connected a candle snuffing element 15 of any suitable design. This snuffing element 15 preferably extends over the flame in a manner to extinguish the same.

The tube 12 is also provided with a curved upper end 16 and is designed to slidably support the taper illustrated in general by the letter B. The taper B projects beyond the end of the tube 12, as best illustrated in Figures 1 and 2.

In order to slidably support the taper B, various means have been provided for anchoring one end of the taper. In the form of construction illustrated the slidable plug 17 is provided with a projecting lug 19 which extends through a longitudinal slot 20 in the tube 12. By means of the lug 19 the plug 17 may be vertically moved longitudinally of the tube 12. A flexible resilient strip 21 is secured to the upper end of the plug 17 and is provided with an aperture 22 through which the end 18 of the taper B may be threaded as best illustrated in Figure 2 of the drawing. Various other means may be provided for supporting the lower end of the taper B, one of these means comprising a resilient clamping socket which clamps opposite sides of the taper end 18.

The taper B is preferably formed as best illustrated in Figure 4 of the drawing, and includes short lengths 23 of taper separated by circumferential grooves 24. The taper is ordinarily formed of wax embodied in a wicking material and obviously the wick acts to connect the lengths 23 of taper. Because of the reduction in thickness of the taper at the grooves 24, the taper will bend readily at these points.

In Figure 5 of the drawing I disclose the taper C formed in any usual or desired manner, such as by impregnating strands of wicking with wax or other suitable material. The taper C differs from the taper B in that the short lengths or sections 25 of taper are separated by transverse fold lines 26. As a result the taper illustrated in Figure 5 will readily fold along a plane intersecting the drawing and arranged at substantially right angles thereto, but will not readily curve in the direction of the plane of the drawing sheet. Accordingly, while the taper C may be bent up or down, the same must be held in proper relation to the tube 12 to do so. Therefore the taper C differs from the taper B in the fact that while the taper B may bend universally in any direction the taper C may bend only in a single plane.

In Figure 6 of the drawing I disclose a taper D which may also be constructed in accordance with the teachings of the present invention. The taper D is formed of wicking material impregnated in wax. The taper is constructed, however, of lengths 27 formed of relatively stiff or rigid wax and separated by shorter sections 29 of a softer wax. As a result the taper D may

4

bend readily at the sections 29, but will not bend readily through the length of the sections 27.

In using the tapers they are first attached to the adjusting mechanism for movement longitudinally of the supporting tube. The taper is then drawn into the tube until the necessary amount projects from the tube. It is preferable that the end of the tube 12 extend to a midpoint between the points of bend of the taper. As a result the taper may be bent along a line spaced from the end of the tube so that the flame has little tendency to heat the end of the tube. By maintaining the flame at a reasonable interval from the end of the tube, the tube will not heat and the flame will normally be above the end of the tube. When the flame reaches one of the points of bend the wax forming the taper has a tendency to fill any groove formed in the taper previously to the time the flame actually reaches the groove. Thus the burning of the taper is in no way affected by providing spaced fold lines therein.

In accordance with the patent statutes, I have described the principles of construction and operation of my taper, and while I have endeavored to set forth the best embodiments thereof, I desire to have it understood that obvious changes may be made within the scope of the following claims without departing from the spirit of my invention.

I claim:

1. A taper of the class described having a wick comprising a series of strands and a wax coating, the coating being formed with a plurality of spaced apart circumferential grooves for the purpose set forth.
2. A waxed taper of the class described having a wick and a flexible coating of combustible material encircling the wick, grooves cut partially through the wax coating, said grooves being spaced substantially an inch apart for the purpose set forth.
3. A taper comprising a wick having a relatively rigid body of combustible material encircling the same, said body having a series of spaced lines of fold therein at which the resistance to bending of the taper is materially reduced.
4. A taper comprising a wick having a relatively rigid body of combustible material encircling the same, said body including a series of spaced circumferential grooves extending thereabout.
5. A taper comprising a wick having a body of combustible material encircling the same, and a series of transverse fold lines at spaced intervals in said body.
6. A self-sustaining wax taper including a wick and a flexible coating of combustible material encircling said wick, grooves in said wax body on opposite sides of said wick to provide a relatively rigid body having somewhat less rigid weakened points of bend at intervals through the length of the taper.

JOHN C. URBANK.
